UNITED STATES PATENT OFFICE

2,272,469

CENTRIFUGAL PUMP

William H. Lannert, Chicago, Ill., assignor to Chicago Pump Company, Chicago, Ill., a corporation of Illinois

Application December 23, 1939, Serial No. 310,673

2 Claims. (Cl. 103—103)

This invention relates to centrifugal pumps of that type which are employed for pumping sewage and other liquids containing solids such as paper, rags, stringy substances, trash and other semi-solids. Considerable difficulty has been encountered in centrifugal pumps of this type because of the likelihood of the rags, paper and other stringy material lodging on or clinging to the heel of the impeller blade in such quantities as to interfere with the operation of the pump and sometimes clogging the same to such an extent that it must shut down. Many attempts have been made to overcome this difficulty with more or less success, and the principal object of this invention is to eliminate the possibility of solids being caught on the heels of impeller blades.

I have accomplished this result by employing an entirely different principle of operation than has been employed heretofore in centrifugal pumps. In accordance with the present invention the interior of the pump is so shaped that the velocity of the liquid is increased as it passes through the eye of the impeller, then decreased in an inlet chamber, and its velocity again increased as it passes the heel of an impeller blade.

The result of this change of velocity of the liquid causes the solids to bunch together as the velocity is slowed up in the inlet chamber, and the increase of velocity immediately thereafter causes the solids to be drawn across the space in front of the heel of an impeller blade, thereby preventing the solids from being caught on the heel. The invention consists, therefore, in the several novel features of construction, arrangement and combination of parts hereinafter fully set forth and claimed.

The invention is clearly illustrated in the drawing accompanying this specification, in which:

Fig. 1 is a central vertical longitudinal section through a centrifugal pump, embodying a simple form of the present invention, with certain parts broken away.

Fig. 2 is a vertical cross section of the impeller taken on the line 2—2 of Fig. 1.

Fig. 3 is a vertical cross section of the impeller taken on the line 3—3 of Fig. 1, and

Fig. 4 is a detailed horizontal cross section taken on the line 4—4 of Figs. 1 and 2.

Referring to said drawing, the reference character 5 designates the base of a centrifugal pump, upon which is mounted a housing 6 containing bearings, one of which is seen at 7, in which is mounted an impeller shaft 8, driven 55

from a suitable source of power such as an electric motor (not shown). Bolted to the housing 6 is one side wall 9 of the pump casing, which side wall may be formed with a housing 10 containing packing 11 around the impeller shaft. Bolted to the side wall 9 is the end wall 12 of the pump casing, which contains the usual volute chamber of the pump. If desired, the other side wall 13 of the pump casing may be cast integral with the end wall 12. The inlet pipe to the pump is shown at 14, and as shown it has a bolting flange 15, rigid on its end, which is bolted to the side wall 13 of the pump casing, as by bolts and nuts 16. The discharge end of the volute chamber is shown at 17. Obviously the construction of the parts above described may be varied to suit the type of pump to which the invention is applied.

The impeller shaft projects into the interior of the pump casing, and the impeller 18 is mounted on its tapered end as by a hub 19; desirably a bolt 20, threaded in the end of the shaft fastens the impeller thereon. The impeller shown is of the closed type; it has two spaced side walls, 21, 22, one of which is formed with the hub 19, and is connected to the other side wall by the impeller blades 23.

The eye 24 of the impeller is of less internal diameter than that of the inlet pipe 14, and the side wall 13 of the casing has a suction inlet 25 disposed in co-axial alignment with the inlet pipe and eye. The face of the suction inlet converges from the internal face of the inlet pipe to the internal face of the eye. If desired, the face of the suction inlet 25 may be convexly rounded (in cross section) as shown. The purpose of the reduction in diameter of the eye as compared with that of the inlet pipe is to increase the velocity of the liquid passing through the eye of the impeller.

The eye opens to an inlet chamber 26 in the impeller, in which chamber the velocity of the liquid is decreased as it passes through it, and this slowing up of the velocity allows the solids to bunch together before proceeding through the passages between the impeller blades.

The heel 27 of each impeller blade is made relatively narrow and is convex or rounded off as seen in Figures 2 and 3, and merges into the inner and outer faces 28, 29 of the blades. Instead of being parallel with the axis of the impeller, the heel of each blade preferably slopes at an angle to the axis of the impeller, and the inner and outer faces of the blades, beginning at the heel, slope from one side wall to the other for a

short distance and gradually merge into the transverse configuration of the blade, which may be parallel with the axis of the impeller, with fillets at the corners formed between the side walls 21, 22 and blades 23. If desired, the channels formed by the side walls and blades may be circular or other rounded contour, as is desired. The inner face 28 of each blade extends in a curvilinear line from the convex face of the heel, running from the curved face of the eye along a line which is non-concentric with respect to the axis of the impeller, and approaches the opposite heel to a point approximately opposite the crown of said heel, whereby the cross sectional area of the passages between the heels and the leading ends of the blades decreases to a point approximately opposite the crown of said heel, and then continues along a curvilinear line approximately concentric with the convex face of the heel of the other blade, and then takes a curvature suitable for most efficient pumping of the liquid, the extremity of the inner face ending at the periphery of the impeller.

The outer face 29 of each blade extends from the convex face of the heel along a curved line substantially paralleling the curvature of the inner face of the tail end of the companion blade and then curves in a direction around but eccentric to the axis of the impeller, and progresses towards the periphery of the impeller along a curved line best adapted for efficiently impelling the liquid. Desirably the tail end of each blade extends for some distance beyond the heel of the companion blade.

As is well understood, the concave inner faces of the impeller blades impart suction upon the liquid and the convex sides thereof serve to impel the liquid from the inlet chamber of the impeller to the volute chamber of the casing. However, by reason of the shape of the forward or entering ends of the sides of the blades, the velocity of the liquid is increased as it passes the heel of a companion blade, and the suction effect of the inner face of each blade adjacent its heel, serves to draw the liquids and solids away from the opposite heel, thereby preventing the solids from being caught thereon.

I claim as new and desire to secure by Letters Patent:

1. A centrifugal pump casing, having a suction inlet and an impeller rotating in the casing, said impeller being formed with an eye and with impeller blades, means to increase the velocity of liquids passing through the eye of the impeller and means to decrease the velocity of the liquid after passing through the eye, each of said impeller blades having a leading end adjacent the eye and a trailing end at the periphery of the impeller, a convex heel at its leading end and inner and outer faces that progress from the convex heel to the periphery on curvilinear lines, the inner and outer curved faces of each blade diverging from the convex heel to provide a thickened part beyond the heel and then converging toward the trailing end, with the inner face of each blade substantially paralleling the convex heel and outer face of the thickened portion of the other blade to form passages between the blades whereby the velocity of the liquid passing through the passageway is increased across the path of travel of the heel.

2. A centrifugal pump comprising a pump casing having a suction inlet which converges toward the interior of the pump casing, an impeller rotating in said pump casing and having an eye of substantially the same diameter as the smallest diameter of the suction inlet whereby the velocity of liquids passing through the eye is increased, said impeller having an enlarged inlet chamber into which the eye opens, said impeller also having impeller blades, each of said impeller blades having a leading end adjacent the eye and a trailing end at the periphery of the impeller, a convex heel at its leading end and inner and outer faces that progress from the convex heel to the periphery on curvilinear lines, the inner and outer curved faces of each blade diverging from the convex heel to provide a thickened part beyond the heel and then converging toward the trailing end, with the inner face of each blade substantially paralleling the convex heel and outer face of the thickened portion of the other blade to form passages between the blades whereby the velocity of the liquid passing through the passageway is increased across the path of travel of the heel.

WILLIAM H. LANNERT.
